UNITED STATES PATENT OFFICE.

CHARLES COLAHAN, OF CHICAGO, ILLINOIS.

GRAIN-BINDER.

SPECIFICATION forming part of Letters Patent No. 748,587, dated January 5, 1904.

Application filed July 13, 1903. Serial No. 165,287. (No model.)

To all whom it may concern:

Be it known that I, CHARLES COLAHAN, a citizen of the United States of America, and a resident of Chicago, county of Cook, and State of Illinois, have invented certain new and useful Improvements in Grain-Binders, of which the following is a specification, reference being had to the accompanying drawings, forming a part thereof.

- 10 My invention has reference to mechanism accessory to tying the knot in binders of the Appleby type, and more particularly to that form wherein the cord-slot of the breastplate has an oblique angular jog having a concentric raised portion with a curved depression on its upper surface beneath the knotter-jaw, over the inner inclined edge of which the cord is laid and by which it is guided close up to the spindle of the knotter, the latter 15 normally standing with its bill trending outwardly in the general direction of the outer or return reach of said jog and past the inclined edge of the inner reach and stopping in such position after each knot-forming revolution.

In a construction wherein the upper surface of the breastplate is flat or open under the knotter it sometimes happens while at work in the field that the jarring of the machine or the pressure of the straw will cause one or both strands of the cord that are around the bundle beneath the breastplate and laid over the angular jog in the cord-slot and over the knotter to the cord-holder, particularly the strand at the outer side of the bundle, to slide around the jog in the cord-slot and displace the cord, so that the two ends leading to the cord-holder will not be seized by the knotter-jaws as the latter close, and thus the knot fails to be formed. To remedy this, I have heretofore shown in Letters Patent No. 690,134, granted to me December 31, 1901, a convex raised boss portion on the upper surface of the breastplate that is provided with a concave depression concentric with and beneath the knotter and terminates in a rounded stop setting across the longitudinal reach of the cord-slot and holds the cord up to the knotter and prevents its 45 escape therefrom in the formation of the knot, as the cord-strands extending around the bundle beneath the breastplate lie within the

concave depression and the knotter has formed the loop and seized the ends of the band extending to the cord-holder and the 55 knot is slipping off toward the point of the knotter by the time it becomes desirable to force the bundle-strands out of the depression in the breastplate, that the knot may readily slip from the knotter with the outgoing bundle. I also refer to the breastplate shown in my Patent No. 677,943, July 9, 1901, having a depression at the inner side of the knotter-jaw in the outer curvature of the upper plane surface of the breastplate, to which the present invention is equally applicable.

My present invention provides means to force the band out of the projecting portion of the breastplate that retains the cord during the formation of the knot and permit the 70 escape of the bundle-strands over the boss or outer portion of the concave depression in the breastplate, as the outward strain on the cord-band by the bound bundle in pulling the loop from the knotter strips it in the process of 75 completing the knot.

My present invention consists in mechanism providing additional forward movement or rotation of the knotter to advance the bundle-strands out of the concave depression in 80 the breastplate as the knot is slipped down toward the outer end of the knotter by the stress of the bundle.

The knotter in my former patents stops after one complete revolution with its point 85 trending outwardly, while my present knotter is given an additional movement, secured by one extra gear and pinion tooth to cause the knotter to revolve slightly farther and lift the bundle-strands out of the depression in the 90 breastplate to permit the egress of the strands across the knotter-face and oblique reach of the cord-slot. This is accomplished by quickly turning the knotter slightly farther forward after it has made one complete revolution and imparting a quick jerk or sudden action back to the knotter to facilitate the outgoing and stripping of the knot with the bundle. This is secured without materially changing the construction of the parts, as the 95 knotter-actuating wheel has a portion of the pinion-holding stop-flange made concave just beyond the extra gear-tooth, which permits the stop-face of the pinion to tilt down suffi-

- ciently to permit the action of the pinion in revolving the knotter slightly beyond its normal position. The pinion stop-flange rises as the extra tooth is passed and rocks the knotter back to its normal position, pointing outwardly, while the binder-arm again lays the cord over the cord-supporting finger that projects across the open slot of the breast-plate and across the knotter to the cord-holder.
- 10 In the drawings, Figure 1 is a plan view showing the knotter in dotted lines over the breastplate in order to clearly exhibit the convex raised portion on the upper surface of the breastplate that is provided with a concave depression concentric with and beneath the knotter and terminating in a rounded stop setting across the longitudinal reach of the cord-slot that holds the cord up to the knotter. In this view the parts are all in their normal position as the cord is laid by the binder-arm over the supporting-finger that extends across the open slot and over the obliquely outwardly-pointing knotter to the cord-holder, (the latter not shown.) Fig. 2 is a view of the same parts after the knotter has made one complete revolution in the formation of the knot. Fig. 3 is a view of the same after the knotter has made the additional further movement with the extra gear-teeth to force the bundle-strands out of the concave depression in the breastplate. Fig. 4 is a view showing the knotter restored to its normal position as the knot escapes with the outgoing bundle, in which position the parts remain for the repetition of the operation, as shown in Fig. 1. Fig. 5 is a side elevation of the knotter drive-wheel, its gear-teeth, and cam-stop. Fig. 6 is a sectional view on line 6-6 of Fig. 5, showing the knotter gear-teeth, and cam-track, also the knotter-pinion, its stop-surface in dotted lines. This view illustrates the action of the parts at the moment the additional movements are being imparted to place the knotter in positions shown in Figs. 3 and 4.
- 45 In the drawings, A represents the breast-plate; A', the knotter; a, the open binder-arm slot in the breastplate; a', the cord-supporting finger in the open slot; B, the depression in the upper raised surface of the breastplate, which is the same as shown in my former patent, No. 690,134.
- B' is the convex raised boss at the outer edge of the depression beneath the knotter-jaw to deflect the escaping strands.
- 50 C is the cam-track, actuating the friction-wheel of the vibrating knotter-jaw.
- D is the knotter drive-wheel; D', its cam-track and stop-motion surface; E, the knotter driving-gear teeth; E', the knotter-pinion; E², the drive-pinions that actuate the cord-holder, (not shown;) e, the extra drive-gear tooth that imparts the additional movement to the extra tooth e' of the knotter-pinion;
- 55 e², the straight cam stop-motion surface track of the knotter-pinion.
- d is the concave surface of the cam-track

of the drive-wheel that admits the turning down of the cam-stop e² as the extra tooth imparts additional rotary movement to the knotter.

d' is the upwardly-inclined surface of the cam-track that restores the pinion and knotter to its normal position.

In operation the band being placed around the bundle over the extended finger in the cord-slot and across the outwardly-pointing oblique knotter-jaw in the usual well-known manner, as indicated in Fig. 1, the knotter performs one complete revolution in formation of the knot, bringing the cord or band as shown in dotted lines in Fig. 2, the bundle-strand extending down around the bundle beneath the breastplate and lying in the depression at the upper side of the knotter, which at this moment gives a quick jerky movement forward, as shown in Fig. 3, which causes the band to slip out of the depression across the face of the knotter and oblique face of the slot, when the reverse movement places the knotter to the position shown in Fig. 4 as the bundle is discharged. As has been stated, this quick forward-and-back movement of the knotter is imparted by the extra gear-teeth and stop-motion that actuates the knotter. There is a further advantage in this extra forward-and-return movement of the knotter after completing its full revolution from the normal position in which it stands with jaws trending outward in the direction of the oblique reach of the cord-slot, which advantage is entirely independent of the depression in the breastplate on the upper side of the knotter. With the normal and stopping position of the jaws trending outwardly the strands extending from the loop laid around the jaws to the holder are not so fully gathered within the jaws and grasped thereby as is desirable, particularly after the parts are worn. The additional movement beyond the complete revolution enables the grasp to be certain, and the return movement to the outwardly-trending position of rest permits the knot to be stripped not only in the usual way, but also in much more reliable condition.

Having thus described my invention, what I claim, and desire to secure by Letters Patent, is—

1. In a grain-binder the combination with a knotter that normally rests with its jaws trending outwardly in the direction of discharge of the bundle, of a stop at the inner side of the knotter for obstructing the escape of the cord-strands leading round the bundle, mechanism for giving the knotter a complete revolution for laying the knot, and mechanism for imparting to said knotter a quick forward and return movement at the conclusion of said revolution, to lift the cord-strands off of the stop and deflect them therepast.

2. In a grain-binder that has its knotter in its normal position pointing obliquely outward, the combination of a breastplate having an open slot terminating in an oblique

reach, having a concave depression at its re-entrant angle below the knotter to temporarily detain the cord-strands during the formation of the knot, with a knotter making one full revolution to lay the knot, and mechanism imparting an onward and return movement to the knotter substantially as shown and described.

3. The combination of the breastplate having an angular slot and the projecting cord-supporting finger over the slot for receiving the cord as the bill rests in its normal position, pointing outwardly parallel with the oblique face of the angular slot, said breast-plate having a depression therein at the re-entrant angle wherein the cord rests in the formation of the knot, and means for imparting to the knotter its knot-lying revolution and a quick forward and backward move- ment after the completion of its knot-lying revolution, to force the cord from the depression and permit it to pass outwardly therefrom in the discharge of the bundle substan- tially as shown and described.

25 4. The combination with the angularly-slotted breastplate having a cord-stop as set forth, of the knotter normally standing with its jaws trending outwardly in the direction

of the oblique reach of the slot, the stop-pin- ion and delay-shoe for said knotter, and the 30 knotter-cam having a delay-track, a rack connecting the terminals of said track and adapted to impart a single revolution to the knotter, an additional tooth to said rack and a de- pression in the track coöperating with said 35 tooth to permit the delay-shoe to dip as the tooth acts, and immediately raising it to en- gagement with the track whereby the knotter is given a quick onward and return move- 40 ment at the termination of its complete revo- lution to release the knot therefrom.

5. The combination with the angularly- slotted breastplate, of a knotter or tying-bill normally standing with its jaws trending out- 45 wardly in the direction of the oblique reach of the slot, mechanism imparting to the knot- ter a single complete revolution from said po- sition of rest, and mechanism imparting thereto at the completion of said revolution, an additional onward and quick return move- 50 ment from and to said position of rest.
